UNITED STATES PATENT OFFICE.

SIMON HAUSLER, OF SAN FRANCISCO, CALIFORNIA.

SAW-FILING DEVICE.

1,409,442.

Specification of Letters Patent. Patented Mar. 14, 1922.

Application filed January 5, 1921. Serial No. 435,157.

To all whom it may concern:

Be it known that I, SIMON HAUSLER, a citizen of the United States, residing at San Francisco, in the county of San Francisco and State of California, have invented new and useful Improvements in Saw-Filing Devices, of which the following is a specification.

This invention relates to saw filing devices 10 and has for its object to provide a device whereby a series of teeth may be filed or sharpened at the same time.

This object I accomplish by employing a frame carrying a number of files or sharpeners properly spaced to correspond with the spacing of the saw teeth, and a guide adapted to be clamped upon the saw and slidably receive the file carrying frame whereby the latter when reciprocated manually, will be 20 guided and held in proper position to file the teeth.

One form which my invention may assume is exemplified in the following description and illustrated in the accompanying 25 drawings, in which—

Fig. 1 shows a plan view of a device embodying my invention,

Fig. 2 shows a side elevation of a file carrying frame,

Fig. 3 shows a sectional view of the complete device in position upon a saw,

Fig. 4 shows an inverted plan view of the guiding device,

Fig. 5 shows a cross sectional view of the 35 file carrying frame,

Fig. 6 shows an inverted plan view of one of the vertical guiding members,

Fig. 7 shows a side elevation of the same.

Referring more in detail to the accompanying 40 drawings I show a file carrying frame A rectangular in form and made up of parallel side bars 10, detachably received in the ends of which are notched plates 11 to receive the corners of files 12, there being six

45 files shown in the present instance. Overlying the files at each end is an upper plate 13 carrying set screws 14 to clamp the files in place. Each of these upper plates 13 carries a handle 15 whereby the file carrying frame is reciprocated. The plates 13 are removably held in place by screws 16 and owing to the detachability of these end plates 11 and 13 other plates may be substituted for the purpose of accommodating a

50 different number of files or files of a different size or spacing.

To cooperate with the frame A I provide a guide B adapted to be clamped in position upon a saw blade and slidably receive the file carrying frame and guide the same properly for filing the teeth. This guide B is formed of a pair of bottom plates 17 spaced a slight distance apart and adapted to receive between them the blade of the saw. Near each end of each of these plates 17 is 60 a cross head 18 pivotally connected to each bottom plate 17 by means of a pin 19, and provided with a vertical flange or plate 18^a to guide the adjacent side of the file-carrying frame. One of the plates 17 has an extension 20 with each side of which cooperates an adjusting screw 21 carried in a lug 22 depending from the adjacent cross head member 18. By slackening one of these adjusting screws and tightening the other the 65 cross heads can be swung angularly in either direction, the bottom plate 17 shifting longitudinally after the fashion of a parallel ruler to accommodate this angular movement of the cross heads. In this way the 70 vertical flanges 18^a are lined up with the cutting edges of the saw teeth and when properly adjusted are clamped in this position by setting both screws 21. These screws being on opposite sides of the saw blade one will 75 contact with the extension 20 and the other will contact with the blade of the saw and thereby they will act to clamp the entire guiding device in place upon the saw blade.

Each of the cross heads 18 has on its bottom portion a leaf spring 23 fastened to the plate at its inner end and cooperating near its outer end with an adjusting screw 24. Thereby the depth to which the guiding device settles upon the saw blade can be ad- 90 justed.

On one of the bottom plates 17 is slidably mounted a gauge bar 25, which at its outer end carries a bifurcated lug 26 to straddle the blade of the saw. In this lug is mounted 100 a clamp screw 27 whereby the gauge bar can be locked in position upon the saw blade. The distance to which this gauge bar can be extended is equal to the distance between the cross heads 18, and in fixing the guiding device upon a saw blade the gauge bar 25 is extended to its full length and fastened in place so that subsequently if it is desired to advance the guiding device for the purpose of filing the next series of teeth this 105 gauge bar will limit the movement of the guide and insure a proper advance. The

side bars 10 of the file carrying frame are provided with downward extensions 28 at each end, which limit the longitudinal movement of the file carrying frame upon the 5 guide B. The lower edge of each of the side bars 10 rides upon a projection 29 formed upon one of the plates 17 of the guide. The height of this projection will determine the depth that the file is permitted 10 to enter the teeth.

In the operation of the device the frame A with the files in place thereon is fitted between the vertical guide plates 18^a and is reciprocated therein manually. The guide 15 plates 18 being angularly adjustable are first set so that the files will be in line with the cutting edges of the teeth. Preferably the guide plates 18^a are provided on their inner faces with balls 30, as shown in Fig. 7, 20 to reduce the friction between the side plates of the file carrying frame and the vertical guide plates. After a series of teeth corresponding in number to the number of files in the frame A have been sharpened the guide 25 is advanced within the limits permitted by the gauge bar 25. This insures that the next adjacent series of teeth will be presented for filing without requiring the operator to check back on his work. The guide B having 30 been reset the gauge bar 25 is then advanced to the limit of its movement and also clamped in position.

Various changes in the construction and arrangement of the several parts herein 35 shown and described may be employed without departing from the spirit of my invention as disclosed in the appended claims.

Having thus described my invention, what I claim and desire to secure by Letters 40 Patent is—

1. In a saw filing device the combination of a file-carrying frame, including parallel side bars and end pieces, the latter being arranged to detachably receive and support 45 a plurality of files, with a guide comprising parallel bottom plates to straddle a saw blade and angularly adjustable cross heads on the bottom plates, said cross heads being provided with vertical flanges forming 50 guides for the side bars of the file carrying frame.

2. A saw filing device comprising a file carrying frame including parallel side bars, end pieces between the side bars formed with 55 notches to receive the files and a handle to each end for connection with said side bars and end plates, each of said handles having a part to overlie the files and carrying a series of set screws whereby to retain the 60 files in place in the notches on said end plates, in combination with a guide adapted to be clamped upon the blade of a saw.

3. A saw filing device comprising a file carrying frame and a guide therefor, said 65 guide including parallel bottom plates to

receive between them the blade of a saw, a cross head near each end of said bottom plates pivotally connected thereto and having a vertical flange to guide the adjacent side of the file carrying frame and means 70 for retaining said guide in place on the saw blade.

4. A saw filing device comprising a file carrying frame and a guide therefor, said guide including parallel bottom plates to 75 receive between them the blade of a saw, a cross head near each end of said bottom plates pivotally connected thereto and having a vertical flange to guide the adjacent side of the file carrying frame, means for 80 retaining said guide in place on the saw blade and means for varying the angular position of the cross heads with relation to the saw blade.

5. A saw filing device comprising a file 85 carrying frame and a guide adapted to be clamped upon the blade of a saw and slidably receive said file frame, said guide including parallel bottom plates between which the blade of the saw is received, a 90 cross head near each end of said plates pivotally connected thereto and having a vertical flange to guide the adjacent side of the file carrying frame and means for varying the angular position of the cross heads, said 95 means also acting to clamp the guide in place on the saw blade.

6. A saw filing device comprising a file carrying frame and a guide adapted to be 100 clamped upon the blade of a saw and slidably receive said file frame, said guide including parallel bottom plates between which the blade of the saw is received, a cross head 105 near each end of said plates pivotally connected thereto and having a vertical flange to guide the adjacent side of the file carrying frame, a pair of adjusting screws carried by one of said cross heads acting in opposite directions against one of said bottom plates for varying the angular position 110 of the cross heads with relation to the saw blades.

7. A saw filing device comprising a file carrying frame and a guide adapted to be 115 clamped upon the blade of a saw and slidably receive said file frame, said guide including parallel bottom plates between which the blade of the saw is received, a cross head near each end of said plates pivotally connected thereto and having a vertical 120 flange to guide the adjacent side of the file carrying frame, a pair of adjusting screws carried by one of said cross heads acting in opposite directions against one of said bottom plates for varying the angular position 125 of the cross heads with relation to the saw blades, said screws being also arranged to clamp the blade of the saw between them,

8. A saw filing device comprising a file carrying frame and a guide therefor, said 130

guide including parallel bottom plates to receive between them the blade of a saw, a cross head near each end of said bottom plates pivotally connected thereto and having a vertical flange to guide the adjacent side of the file carrying frame and means for retaining said guide in place on the saw blade, and a gauge bar slidably mounted on one of said bottom plates for determining the limit of advance of the guide.

9. A saw filing device comprising a file carrying frame and a guide therefor, said guide including parallel bottom plates to receive between them the blade of a saw, a cross head near each end of said bottom plates pivotally connected thereto and having a vertical flange to guide the adjacent side of the file carrying frame, means for retaining said guide in place on the saw blade, a gauge bar slidably mounted on one of said bottom plates for determining the limit of advance of the guide and clamping means carried by said gauge bar.

10. A saw filing device comprising a file carrying frame and a guide therefor, said

guide including parallel bottom plates to receive between them the blade of a saw, a cross head near each end of said bottom plates pivotally connected thereto and having a vertical flange to guide the adjacent side of the file carrying frame, means for retaining said guide in place on the saw blade, and a bearing ball carried by each of said vertical flanges for cooperation with the sides of the file carrying frame.

11. A saw filing device comprising a file carrying frame and a guide therefor, said guide including parallel bottom plates to receive between them the blade of a saw, a cross head near each end of said bottom plates pivotally connected thereto and having a vertical flange to guide the adjacent side of the file carrying frame, means for retaining said guide in place on the saw blade and means on the under side of each of said cross heads for contact with the teeth of the saw, said means being adjustable to regulate the degree to which the guide settles upon the blade of the saw.

SIMON HAUSLER.
